CAMERA SUPPORT BRACKET FOR A TRIPOD

Richard B. Jones, 930 W. Edgehill Road,
San Bernardino, Calif.

Filed June 18, 1971, Ser. No. 154,705

Term of patent 14 years

Int. Cl. D16—05

U.S. Cl. D61—1

FIG. 1 is a left side elevational view of a camera support bracket for a tripod showing my new design.

FIG. 2 is a rear elevational view thereof.

FIG. 3 is a right side elevational view thereof.

FIG. 4 is a front elevational view thereof.

FIG. 5 is a top plan view of FIG. 2.

FIG. 6 is a bottom plan view of FIG. 2.

I claim:

The ornamental design for a camera support bracket for a tripod, as shown and described.
